UNITED STATES PATENT OFFICE

2,687,100

STABILIZER FOR RAILWAY CAR TRUCKS

George E. Dath, Mokena, Ill., assignor to W. H. Miner, Inc., Chicago, Ill., a corporation of Delaware

Application March 12, 1949, Serial No. 81,114

1 Claim. (Cl. 105—197)

1. This invention relates to improvements in railway car trucks, and more particularly to means for stabilizing the action of the same.

One object of the invention is to provide in a railway car truck, simple and efficient means for snubbing the action of the usual truck springs and also yieldingly controlling relative lateral motion of the truck bolster and side frame of the truck.

A more specific object of the invention is to provide means of the character indicated in the preceding paragraph, comprising a friction clutch connected to the truck bolster, composed of spring pressed friction shoes and a cooperating wedge block, wherein the shoes have sliding frictional engagement with the truck side frame to snub the action of the truck springs, and the shoes and wedge block are laterally slidable on each other to frictionally resist lateral motion of the bolster and side frame of the truck.

Other objects of the invention will more clearly appear from the description and claim hereinafter following.

In the accompanying drawings forming a part of this specification, Figure 1 is a side elevational view of one of the side frame members of a railway car truck and the associated truck bolster and springs, illustrating my improvements in connection therewith. Figure 2 is a vertical sectional view, on an enlarged scale, partly broken away, corresponding substantially to the line 2—2 of Figure 1. Figure 3 is a longitudinal vertical sectional view, partly broken away, corresponding substantially to the line 3—3 of Figure 2. Figure 4 is an end elevational view of the right hand side portion of the truck bolster, illustrated in Figure 1, with the friction shoes and springs omitted. Figure 5 is an elevational view of Figure 4, looking from right to left in said figure, said view being partly broken away. Figure 6 is an elevational view of the right hand friction shoe shown in Figure 2, looking from left to right in said figure. Figure 7 is an elevational view of Figure 6, looking from left to right in said figure.

In said drawings, 10 indicates one of the side frame members of a railway car truck, which is in the form of a casting, and has top and bottom members 11 and 12, connected by vertically disposed sections 13—13. As will be understood by those skilled in this art, the railway car truck includes two such side frame members 10—10, a truck bolster 14, and two clusters of truck springs 15—15, one cluster of which is supported on the bottom member 12 of each side frame. The opposite ends of the bolster 14 are guided

2 between the sections 13—13 of the side frames and the bolster is supported by the two clusters of truck springs. The truck bolster supports the usual body bolster of the car in a well-known manner. As shown most clearly in Figures 1 and 3, the sections 13—13 are inwardly offset at the upper ends thereof, as indicated at 16—16, to provide guides 116—116 between which the bolster 14 is slidable in vertical direction. The offset portions 16—16 of the sections 13—13 include inner and outer webs 17 and 18 which, together with similar webs on the top and bottom members 11 and 12, form inner and outer side walls of the casting. The inner surfaces of the webs 17 and 18 present vertically disposed, flat surfaces 19—19, which are utilized as friction surfaces in my improvements. As shown in Figures 2 and 3, the side walls of each side frame, at the upper ends of the sections 13—13, are braced by horizontally disposed wall portions 20—20 extending between the webs 17 and 18.

My improved mechanism comprises broadly a pair of friction shoes A—A in sliding engagement with the friction surfaces 19—19 of the webs 17 and 18 of the side frame of the car, a wedge B fixed to the bolster of the car and having wedging engagement with the shoes A—A, and springs C—C pressing the shoes A—A against the wedge B.

In carrying out my invention, I provide laterally outwardly projecting, vertical flanges 21—21 on the bolster 14 at opposite sides of each end of the same, the flanges at one end of the same only being illustrated in the drawing.

Each projecting flange 21 of the bolster extends into the space between the webs 17 and 18 at the corresponding side of the side frame 10 and has a horizontal follower plate 22 at the lower end thereof formed integral therewith. The follower plate 22 projects from opposite sides of the flange 21, as clearly shown in Figures 2 and 5.

The wedge B is in the form of a block at the upper end of the flange 21, being formed integral therewith and projecting from opposite sides of said flange, as shown in Figures 2 and 5. The wedge B presents inner, relatively blunt, wedge faces 23—23 of V-shaped, transverse section, respectively opposed to the oppositely projecting portions of the follower plate 22, these wedge faces extending transversely of the wedge.

The friction shoes A—A are of similar design, being disposed at opposite sides of the flange 21. Each shoe A has a lateral inward enlargement 26 at its upper end, presenting an inner wedge face

24 of V-shaped, transverse cross section at the upper end engaging the corresponding V-shaped wedge face 23 of the wedge block B. On the outer sides, the shoes A—A have lengthwise extending, vertical friction surfaces 25—25, which are slidingly engaged with the friction surfaces 19—19 of the webs 17 and 18 at the corresponding side of the side frame. The enlargements 26—26 of the shoes A—A present transverse, flat abutment faces 27—27 at the inner or lower ends.

The springs C—C are disposed at opposite sides of the flange 21, being interposed between the shoes A—A and the follower plate 22, each spring being in the form of a helical coil, having its top and bottom ends bearing, respectively, on the flat abutment face 27 at the inner or lower end of the enlargement 26 of the corresponding shoe and the upper side of the follower plate 22, the abutment face 27 and the follower plate portion at the corresponding side of the flange 21 being preferably provided with centering projections 28—28 engaged within opposite ends of the springs. The springs C—C are preferably under initial compression, thereby pressing the shoes against the wedge to spread the same apart into tight frictional engagement with the friction surfaces 19—19 of the side frame 18.

As will be evident, up and down movement of the bolster 14 is frictionally resisted by sliding frictional engagement between the spring pressed friction shoes A—A and the interior friction surfaces 19—19 of the side frames of the car truck, thus effectively snubbing the action of the truck springs, both during compression and recoil thereof. Further, the lateral motion of the truck bolster is stabilized by the cushioning action of the spring pressed shoes A—A, which are in sliding frictional engagement with the wedge faces of the wedge block B, the shoes being displaced laterally with respect to the wedge B during lat-

eral movement of the bolster with respect to the side frames, and being returned to centered position by the wedging action of the wedge B on the shoes A—A.

5 I claim:

In a railway car truck, including side frames and a transversely extending bolster supported by springs on said side frames, the combination with opposed, interior, vertically extending friction surfaces on each side frame at opposite sides of said bolster, said surfaces lying in planes at right angles to the length of said bolster; of laterally projecting, vertical flanges on said bolster at opposite sides of each end of the same, each 10 of said flanges at each end of said bolster extending between the opposed friction surfaces at the corresponding side of the corresponding side frame; a transverse follower at the lower end of each of said flanges projecting from opposite sides of the corresponding flange; a block 15 at the upper end of each of said flanges formed integral therewith and having transverse wedge faces at its lower end; a pair of friction shoes at opposite sides of each of said flanges having vertically extending friction surfaces on their outer sides engaging the corresponding opposed friction surfaces of said corresponding side frame, 20 said shoes having transverse wedge faces at their upper ends in wedging engagement with the wedge faces of said block; and springs under compression interposed and reacting between said 25 shoes and follower.
